Primary Examiner—Cynthia E Ramirez*(74) Attorney, Agent, or Firm*—Steptoe & Johnson LLP(57) **CLAIM**

The ornamental design for a multi-position mechanic's creeper, as shown and described.

DESCRIPTION

FIG. 1 is a perspective view, depicting a multi-position mechanic's creeper of the present invention;

FIG. 2 is a perspective view, depicting the underside of the multi-position mechanic's creeper of FIG. 1;

FIG. 3 is a top view, depicting the multi-position mechanic's creeper of FIG. 1;

FIG. 4 is a side view, depicting the multi-position mechanic's creeper of FIG. 1;

FIG. 5 is a perspective view, depicting the multi-position mechanic's creeper of FIG. 1 in an inclined seating configuration; and,

FIG. 6 is a perspective view, depicting the multi-position mechanic's creeper of FIG. 1 in an upright seating configuration.
